UNITED STATES PATENT OFFICE.

CHARLES A. VAUGHN, OF VINELAND, NEW JERSEY.

POWER-HAMMER.

SPECIFICATION forming part of Letters Patent No. 606,370, dated June 28, 1898.

Application filed April 17, 1896. Serial No. 588,056. (No model.)

To all whom it may concern:

Be it known that I, CHARLES A. VAUGHN, a citizen of the United States, residing at Vineland, in the county of Cumberland and State of New Jersey, have invented certain new and useful Improvements in Power-Hammers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to power-hammers, and particularly to that type of hammer commonly known as an "upright cushioned strap hammer;" and the hammer which I have made the subject of this application is an improvement on the hammers covered by Letters Patent of the United States, Nos. 412,809 and 459,092, granted to me. The present hammer, while it embodies many of the valuable features of construction set forth in the patents referred to, includes certain improvements and additions which I have discovered are advantageous and productive of better results in the use of power-hammers than the constructions referred to, and the present form of hammer overcomes some defects which have developed and certain objections which have arisen in the practical operation of hammers made in accordance with my former patents.

In the detailed description which follows reference is had to the accompanying drawings, in which—

Figure 1 is a side elevation of the hammer. Fig. 2 is a central vertical section. Fig. 3 is a detail view to illustrate the belt-tightener and brake. Fig. 4 is a detail plan view of the hammer-head-operating lever. Fig. 5 is a detail sectional view of the hammer-head and its guide-plates, taken on line 6 6, Fig. 2. Fig. 6 is a detail view of the belt-tightener and its adjusting devices. Figs. 7, 8, 9, 10, 11, and 12 are detail views of the various parts, to which reference will be made hereinafter.

Referring to the drawings by letter, A denotes the frame of the hammer, which is similar in construction to the frame of the ham-

mers shown in my patents referred to, having two side plates joined at suitable points by webs *a*, the whole being cast in one piece or 55 built up out of several pieces, as desired. The anvil *B* is secured to the front of the frame *A*, as shown in Figs. 1 and 2, by means of the straps or bands *b*, which pass around said anvil and are secured to ears *b'* on the 60 frame *A*. The anvil *B* is preferably recessed into the face of the frame *A*, as clearly shown in Fig. 2. The anvil-die *C*, if one be used in connection with the hammer, is suitably keyed or otherwise removably secured to the 65 anvil *B*.

Directly above the anvil *B* and its die *C* is the hammer-head *D*, which is slidably mounted in guides *D'*, provided with V-shaped grooves in which ribs *d* on the hammer *D* fit, 70 so as to insure the proper right-line movement of the hammer in its rising and falling. The guides *D'*, which consist of heavy plates, are bolted or otherwise suitably secured to the main frame *A* by means of the bolts *d'* 75 and *d*², said bolts *d'* passing through the guides and through flanges *a'* on the main frame *A*, while the bolts *d*² pass through the guides and frame *A* at right angles to the bolts *d'*. Said bolts *d*² serve as adjusting-bolts for the 80 guides *D'*, and by tightening these bolts the guides *D* may be forced together to compensate for wear. To insure the said guide-plates *D'* maintaining the same position relative to the hammer-head *D* to which they are 85 adjusted, I provide springs *d*², Fig. 5, which normally force the guide-plates outwardly, thus giving them a spring-grip upon the hammer-head *D*. The said hammer-head, as clearly shown in Fig. 2, is provided near its 90 top with an aperture *d*⁴, flaring on both sides, through which passes the lifting-strap *E*, the aperture *d*⁴ having the convex faces against which the strap *E* bears. Any suitable die *C'* to coöperate with the die *C* on the anvil is 95 keyed to the face of the hammer. Said strap *E*, which is of leather, canvas, or any suitable flexible material, is preferably made of several thicknesses of material reinforced at its ends on the inside of the loops, as shown 100 in Fig. 7. Said strap is supported at one end at the forward curved extremity of a lever *F* or "helve," as it is commonly called, which lever, as shown in Figs. 2 and 4, is made of

two similarly-shaped plates or bars $f f'$, curved upwardly and then downwardly at their ends, said plates extending to the rear part of the frame A, where they are pivoted to a cushioned support or bearing, which will be referred to hereinafter. Said bars are connected at their forward ends by a bolt f^2 , which passes through a bushing f^3 , and on this bushing one end of the strap E is hung. The other end of the strap E is supported on a similar bushing g, carried by a hanger G, which is suspended from the bars $f f'$ of the helve F by means of a bolt g', the lower end of the hanger G being provided with a bolt 15 passing through bushing g, which supports the other end of said strap E. Said hanger G is cushioned, so as to absorb the shock incident to the blow of the hammer and relieve the operating mechanism from the jar 20 by means of the devices which I shall now describe.

Pivoted to the helve F at the rear of the hanger G is a rod g⁵, which passes loosely through the hanger G and through a rubber 25 or spring cushion g⁴, which bears against the face of the hanger G. I preferably place a cup-shaped metal disk g⁵ against the other side of the cushion g⁴ to serve as an abutment against which the nut g⁶ on the end of the rod 30 g⁵ bears. It will be seen that the blow of the hammer D upon the strap E either in rising or falling will be communicated to the hanger G and the shock of said blow absorbed by cushion g⁴.

35 As hereinbefore stated, the helve F is pivoted at the rear of the machine-frame A to a support or bearing, said bearing consisting of merely an upright H, secured to the frame by bolts h and provided with an interposed cushioning device h', as shown in Fig. 2.

Having described the hammer and its immediate operating mechanism, I will now proceed with a description of the connections between the driving-shaft and the said lever, 40 by means of which power is communicated to the latter and the hammer operated.

The helve or lever F, it is obvious, is a lever of the third class and, as will be seen, is connected with its operating-pitman at a point 45 between its fulcrum and the weight. Said helve F is secured to the pitman J, by which it is operated, by means of a yoke j, Fig. 8, which has the clamping portions j', which surround the two plates $f f'$ of the helve or lever F and are clamped in any position to which the yoke is adjusted by means of the bolt j², passing through the upper part of the yoke. It will be seen that adjustment of this yoke j on the lever F will lengthen or shorten 55 the stroke of the hammer, as the case may be. Said yoke is provided with a journal-bearing j³, on which the brasses or boxes j⁴ of the upper end of pitman J have their bearing, said boxes j⁴ being carried by the open-sided housing J', the necessary adjustment to take up wear of the boxes j⁴ being secured by means 60 of the bolt j⁵ at the front of the housing. I

provide a strap j⁸, which is mounted on one of the drums of the helve F and serves as an abutment against which the yoke j bears. I 70 have provided for a second adjustment of the pitman longitudinally to regulate the stroke of the hammer by screw-threading the depending portion j⁶ of the housing J' and supporting it in a screw-threaded sleeve K, which 75 is in turn adjustable in the split upper end of the pitman in which it is threaded, and securely clamped by means of the clamping-ring k. A lock-nut j⁷ is provided, by means of which the housing J' is locked in its adjusted 80 position in the screw-threaded sleeve K. By these devices the stroke of the hammer may be finely adjusted without changing the position of the yoke j.

The lower end of pitman J is forked, as 85 shown, and at its bottom connected by a transverse web L. This web L is secured by bolts m to the eccentric-strap M, which is securely clamped to the eccentric or crank of the driving-shaft crank N by means of a bolt n. On 90 either side of said web L, I place the cushioning devices m', either of rubber or springs, which give an elastic support for the pitman J and effectually absorb the force of the shock caused by the blow of the hammer and 95 prevent its being transmitted to the driving-shaft N. By making the pitman J forked, as shown, I provide an open passage through the center of the hammer-frame, so that a rod of considerable length can be worked upon 100 the anvil by passing it through the open frame and forked pitman. Said driving-shaft N is journaled in suitable bearings on either side of the frame A and is provided at one end with a driving-pulley N', which is driven by 105 means of a belt O. To tighten said driving-belt O, I make use of the following mechanism: Pivoted to the frame A is a treadle P, the arms p p' of which extend on either side of the frame. To the arm p is attached a rod 110 or link p², which is secured at its upper end to a lever p³, pivoted on a journal-pin or gudgeon p⁴, carried by a plate R, provided with a pivot-pin r, which is in turn mounted in a bearing r' in the machine-frame A. The upper portion of said plate R has a slot r² formed 115 therein through which a clamping or adjusting screw-bolt r³ passes and holds the plate R upon the frame of the machine. It will be apparent that by loosening the bolt r³ the 120 plate R, with its gudgeon p⁴, may be swung on its pivot r and adjusted to various positions to vary the position of the lever p³. Said lever p³, as stated, is mounted on said 125 gudgeon p⁴ and is provided with a slotted scroll or plate p⁵. Hung from said gudgeon p⁴ is a depending rod or hanger S, on which is mounted a pulley s, which bears against the belt O. The hanger S is adjustably secured 130 to the lever p³ by means of a screw-bolt p⁶, which passes through said hanger and the slot p⁷ in the plate p⁵. It will be seen that two adjustments are thus secured for the belt-tightening pulley s, one by the adjust-

ment of the rod or hanger S relative to the lever p^3 and another by the adjustment of the gudgeon-plate R, which carries the lever p^3 , relative to the frame A. By the above construction the belt-tightening pulleys may be made to press more or less tightly against the belt O, when the treadle P is depressed, by giving the various parts described the necessary adjustments.

To automatically throw the belt-tightener out of action and stop the rotation of the shaft N and the operation of the hammer as soon as the treadle P is released, I provide a weighted lever T, which is pivoted to the frame A and has a hooked end t, which engages the lower edge of arm p of lever P. A weight t' normally tends to raise the lever P and relieve the belt O from the pressure of the belt-tightening pulley s. Said weighted lever T also forces a brake-block t'', carried by arm p' on the other side of the frame A, (see Fig. 1,) against a brake-wheel U, carried at the opposite end of the driving-shaft N from the driving-pulley N' and insures the immediate stoppage of the driving-shaft and hammer when the belt is relieved from driving-pressure. The said wheel N' is provided with a suitable counterbalance n' to balance the hammer and its operating mechanism and insure the stopping of the driving-shaft N when the crank and hammer are in their uppermost positions.

The operation of my improved hammer is as follows: The operator depresses the treadle at the front of the machine and releases the brake mechanism, at the same time bringing the belt-tightener into action. Under the action of the belt the cranked driving-shaft is revolved and through its forked pitman operates the hammer-helve, which raises the hammer-head and allows it to descend and deliver its blow to the work upon the anvil beneath. It will be seen that the various working parts of the hammer are carefully guarded against the constant and destructive shock of the blows of the hammer by cushioning devices, so as to avoid all possible injury to said parts, a thing which is so apt to occur in machines of this character. The adjustments which I have provided to enable the operator to produce hammer-blows varying in force are of great advantage. The yoke on the hammer-helve can first be moved to approximately the proper position to cause the hammer to deliver a blow of the required force, and then by means of the screw-threaded connections between the pitman and yoke a finer adjustment may be secured and the blow regulated to a degree of nicety which is very advantageous. By making the main frame of the machine open through its center and forking the pitman, as shown and described, I am enabled to handle work of any length beneath the hammer longitudinally thereof and at the same time preserve the compact form of the hammer and close assembling of the elements of which it is com-

posed, thus avoiding the disadvantages incident to a hammer built with its coöperating elements separated one from the other to permit work of considerable length to be handled thereon.

Having thus described my invention, I claim and desire to secure by Letters Patent—

1. In a power-hammer, the combination with a supporting-frame having an open central portion, of a cranked driving-shaft mounted in said frame, an eccentric-strap mounted on the crank of said shaft, a forked pitman secured to said eccentric-strap, a hammer-helve or operating-lever pivoted to the supporting-frame, connections between said forked pitman and helve, a hammer-head carried at the forward end of said helve, guide-plates on the frame between which said hammer-head slides, and an anvil secured to the said supporting-frame beneath said hammer.

2. In a power-hammer, the combination with a supporting-frame having an open central portion, of a cranked driving-shaft mounted in said frame, an eccentric-strap mounted on the crank of said shaft, a forked, spring-cushioned pitman secured to said eccentric-strap, a hammer-helve or operating-lever pivoted to the supporting-frame, adjustable connections between said forked pitman and helve, a hammer-head carried at the forward end of said helve, spring guide-plates on the frame between which said hammer-head slides, and an anvil secured to the said supporting-frame beneath said hammer.

3. In a power-hammer, the combination with a supporting-frame having a central opening therethrough, of a cranked driving-shaft mounted in suitable bearings in said frame, an eccentric-strap carried by the crank of said shaft, a forked pitman elastically secured to said eccentric-strap, said forked pitman having a split upper end in which is adjustably mounted an open-sided housing in which housing are carried journal-boxes, a hammer-helve or operating-lever pivoted at the rear of the main frame, an adjustable yoke carrying a journal to be held between the boxes at the upper end of the pitman supported by said hammer-helve, a flexible strap carried at the forward or free end of said hammer-helve, said strap being supported at its rear end by a cushioned hanger depending from the said operating-lever, a hammer-head supported by said strap, grooved spring guide-plates adjustably mounted on the main frame between which said hammer-head slides and a suitable anvil below said hammer.

4. In a power-hammer, the combination with the main frame having a central opening, of a driving-shaft mounted in said main frame, a forked pitman carried by said driving-shaft, a hammer-helve or operating-lever pivoted at the rear of said main frame, adjustable connections between said pitman and said operating-lever, a flexible strap supported at the forward end of the hammer-helve, a cush-

ioned hanger depending from said hammer and supporting the rear end of said strap, a hammer-head having an aperture through which said flexible strap passes, grooved 5 guide-plates between which the hammer-head slides, said guide-plates being provided with rearwardly-extending lugs, springs interposed between said lugs and the main frame to normally force the spring-plates out- 10 wardly, and bolts securing said plates to the frame, so as to permit adjustment of said plates relative to the main frame.

5. In a power-hammer, the combination of the main frame A having a central opening, 15 of the driving-shaft N mounted in said main frame, an eccentric-strap M carried by said shaft, a forked pitman J having a transverse web L at its lower end, said web being adapted to be secured between elastic cushions m' in 20 order to give an elastic support for said pitman, said pitman having a split upper end, a sleeve K screw-threaded into the split end of said pitman, a housing j' having a depending portion j⁶ screw-threaded into said sleeve, 25 boxes j⁴ carried by said housing, a hammer-helve or operating-lever F, a yoke j² adjustably mounted on the said hammer-helve, a journal j³ carried by said yoke on which the boxes j⁴ have their bearing, a strap E one end 30 of which is supported at the extreme forward end of said hammer-helve F, a depending hanger G by which the rear end of said strap is supported, a rod g³ pivoted to the hammer-helve and passing through the hanger G, and 35 a cushioning device carried at the free end of said rod to receive the impact of the hanger, a hammer-head D carried by said strap, grooved spring guide-plates d' between said hammer, and an anvil B beneath said hammer.

40 6. In a power-hammer, the combination with a main supporting-frame having a central opening, of a driving-shaft mounted in said frame, an eccentric-strap carried thereby, a forked pitman elastically supported on 45 said strap, a hammer-helve pivoted at the rear of the main supporting-frame, adjustable connections between the said forked pitman and said hammer-helve, a hammer-head operated by said hammer-helve, a treadle piv- 50 oted to the main frame, a brake carried by said treadle, a weighted lever pivoted on the main frame engaging said treadle and normally forcing said brake against the brake-wheel mounted on the driving-shaft, and a

belt-tightener adjustably secured to the main 55 frame and connected with said foot-treadle so that when the treadle is depressed and the brake released said belt-tightener is thrown into operative relation to the belt and the driving-shaft is rotated.

7. In a power-hammer, the combination with the main frame, of the driving-shaft and hammer-operating mechanism, a pivot-pin or gudgeon adjustably mounted on said main frame, an operating-lever carried by said 65 gudgeon, a belt-tightener pulley supported by said gudgeon and adjustable therewith, means for securing an independent adjustment of said belt-tightening pulley relative to said gudgeon, an operating-treadle, and a 70 connecting-rod between said operating lever and treadle.

8. In a power-hammer, the combination with the main frame, of the driving-shaft, the hammer-operating mechanism, and belt-tightening devices consisting of the plate R pivoted to the main frame, a gudgeon carried by 75 said plate, a lever p³ mounted on said gudgeon, a belt-tightening pulley s, a hanger S by which said pulley s is supported, adjustably 80 secured to said lever p³, an operating-treadle P and a rod p² connecting said treadle and lever p³.

9. In a power-hammer, the combination with the main frame, of a driving-shaft, ham- 85 mer-actuating mechanism operated thereby, a belt-tightener for said driving-shaft consisting of the plate R pivoted to the main frame, said plate R having an upper slotted portion by means of which said plate may be 90 adjusted to various positions, a gudgeon p⁴ carried by said plate R, a lever p³ mounted on said gudgeon, said lever having a slotted scroll or plate p⁵, a depending rod or hanger S mounted on said gudgeon, a screw-bolt p⁶ 95 by which said hanger S is adjustably secured to the slotted scroll or plate p⁵, a belt-tightening pulley s supported by said hanger S, a treadle P and a rod p² connecting said treadle and lever p³.

In testimony that I claim the foregoing I have hereunto set my hand this 6th day of March, 1896.

CHARLES A. VAUGHN.

Witnesses:

ALEX. M. TAYLOR,
F. S. S. JOHNSON.
